United States Patent Office

Des. 218,002
Patented July 7, 1970

218,002

REGISTRATION CERTIFICATE HOLDER

Gordon R. Cobbs, Des Moines, Iowa, assignor to Cobbs
Manufacturing Company, Des Moines, Iowa, a corporation of Iowa

Filed Aug. 11, 1969, Ser. No. 18,644

Term of patent 14 years

Int. Cl. D20—03

U.S. Cl. D96—3

FIG. 1 is a front perspective view of a registration certificate holder showing my new design; and
FIG. 2 is a rear perspective view thereof.

I claim:

The ornamental design for a registration certificate holder, substantially as shown.
